BUILDING CONSTRUCTION

Thomas J. Foster, Ridgewood, N. J., assignor to
 Larry Foster Foundation, Montclair, N. J., a
 corporation of New Jersey

Application March 16, 1945, Serial No. 583,082

4 Claims. (Cl. 72—77)

1

This invention relates to building constructions. More particularly it pertains to constructions which are at least in part of a prefabricated nature and wherein foundation girders are provided on piers or footings which extend below the frost line.

It has been customary in the past to fasten a building or other permanent structure to a foundation set in the earth. Holes are dug in the ground and then forms and templates are positioned in the holes and finally concrete is poured into the forms and around the templates. Thereafter horizontal girders or beams are positioned upon the poured foundations and are secured thereto with the aid of the templates. Ordinarily, in spite of what precautions may be taken, it is necessary to drill the girders at the building site and otherwise labor over the foundations in order to align them with the rigidly fastened templates and secure them to the earth.

I have discovered a procedure whereby the poured footings and piers may be secured to previously squared and leveled foundation girders, so that the girders may first be located in their correct positions without regard to piers or footings. Thereafter poured concrete supports extending below the frost line are attached to the aligned foundation girders. Accordingly it is an object of my invention to provide a method of operation whereby the foundations for a building may be squared and leveled and secured to the earth in a manner which overcomes the above-described and other well-known difficulties which have arisen in past foundation constructions. Other objects will be in part pointed out as the description proceeds and will in part become apparent therefrom.

The invention accordingly consists in the features of construction, combinations of elements, arrangements of parts and methods of operations as will be exemplified in the structures and sequences and series of steps to be hereinafter indicated and the scope of the application of which will be set forth in the accompanying claims.

Figure 1 is a plan view of the foundations of a simple structure embodying the invention;

Figure 2 is a perspective view of a part of a precast concrete foundation girder;

Figure 3 is a perspective view of a combination base plate and tie plate used in practicing the invention;

Figure 4 is a sectional view taken along the line 4—4 of Figure 1; and

Figure 5 is a perspective view of an assembly construction illustrating the invention.

In Figure 1 a series of girders 20 are shown laid

2

out in rectangular configuration and connected one to another by means of base plates 22. Each girder 20 (see Figure 2) is provided at its ends with girder studs 24 which are precast in the reinforced concrete of the girders. Figure 3 illustrates in greater detail the type of construction of a base plate 22 wherein a pair of tie plates 26, each provided with a tie slot 27, are shown welded to the upper surface of plate 22 and with anchor bolt 28 extending downwardly through base plate 22 to secure the plate in a concrete footing. In Figure 4 a base plate 22 is illustrated bolted to a girder 20 by means of a nut 29 on girder stud 24. Anchor bolt 28 extends downwardly and a concrete footing 30 has been poured under base plate 22. In Figure 5 a construction similar to that shown in Figure 4 appears but with the addition of a column 32 provided with slots 34 which has been slid downwardly over girder stud 24 and is held in place upon base plate 22 by nut 29. I use these and other similar constructions in carrying out the operations of my invention.

If a building is to be erected on a relatively flat lot, I begin by digging holes at the locations where vertical building columns are to be erected and I connect these holes with shallow trenches of sufficient width and proper depth to receive horizontal foundation girders laid out according to the floor plan of the building. Illustratively, I use 10 a precast, reinforced concrete foundation girder such as girder 20 which I manufacture at a central location and bring to the site of construction by truck. I locate the foundation girders in the prepared trenches with the aid of a small tractor derrick and having set them out in accordance with the floor plan of the building, I connect their adjacent ends, as by slotted steel tie plates of constructions along the lines illustrated in Figure 3. These tie plates cooperate with the girder studs to form a relatively flexible connection between the ends of adjacent girders, in the sense that they hold in proper abutment the ends of the girders but permit limited angular movement of one girder with respect to another. It is then a 15 simple matter with the aid of a tractor derrick to level the girders and temporarily wedge and otherwise secure them in place in their trenches, and to square the various corners and align the intermediate connections. Having done this I pour concrete into the holes at the various points where columns are to be erected and ordinarily under each girder connection in such fashion that the base plates 22 and anchor bolts 28 are imbedded in the upper portions of the soft concrete. 20 After the concrete is hard I back off the nuts from

the girder studs and slip slotted columns downwardly over the studs, as illustrated in Figure 5, and then solidly bolt the columns in vertical position.

It is to be observed that the base plates and tie plates do not necessarily have to be integrally constituted and that separate base plates may be added after appropriate tie plates have been used to connect adjacent foundation girders. With this construction it is a simple matter to lay out the foundation girders rapidly and to align them and thereafter to pour as deep and as large and as many concrete piers and footings as the particular building site and type of construction may require. Thus the building site becomes a place of assembly only and the various components which are used there may previously be prepared at one central location where heavy machinery is available, efficient methods of operation may be maintained, and temporary weather conditions can have no adverse effects or cause building delays. And having prepared the various components, they can be rapidly assembled at the site of the building with assurance that an absolutely true foundation will result and with a minimum loss of labor and materials in the field.

From the foregoing it will be observed that a method of building construction embodying my invention is well adapted to attain the ends and objects hereinbefore set forth, and to be economically executed, since all parts of the procedure are thoroughly practicable over a wide variation of modifications as may be desirable in adapting the invention to different applications. The invention provides, at a minimum of labor, an exact foundation which allows the steel structure to be erected without trouble.

As many embodiments may be made of the above invention and as many changes may be made in the embodiments above set forth, it is to be understood that all matter hereinbefore set forth or shown in the accompanying drawings is to be interpreted as illustrative and not in a limiting sense.

I claim:

1. In the art of erecting buildings of the type having concrete footings, that improvement which includes the steps of digging holes where columns are to be erected, digging trenches between the holes for receiving foundation girders, laying girders in the trenches, flexibly connecting the girders where they abut one another, squaring and leveling the girders, pouring concrete footings into the holes to support the girders at their connected ends, and erecting the

structure of a building upon said girders as a foundation.

2. In the art of erecting buildings of the type having concrete footings, that improvement which includes the steps of digging holes where columns are to be erected, digging trenches between the holes for receiving foundation girders, laying girders in the trenches, flexibly connecting the girders where they abut one another, squaring and leveling the girders, providing a column base plate wherever a column is to be erected, pouring concrete footings into the holes to support the girder connections and column base plates, and erecting the structure of a building upon said girders and plates as a foundation.

3. In the art of erecting buildings of the type having concrete footings, that improvement which includes the steps of digging holes where columns are to be erected, digging trenches between the holes for receiving foundation girders, laying girders in the trenches, flexibly connecting the girders where they abut one another by means of column base plates having girder tie plates secured thereto, squaring and leveling the girders, pouring concrete footings into the holes to support the girder connections and base plates, and erecting the structure of a building upon said girders and plates as a foundation.

4. In the art of erecting buildings at a building site, that improvement which includes the steps of prefabricating foundation girders provided with connection portions for flexible connection to one another and for support of vertical columns, digging holes at the building site where columns are to be erected, digging trenches between the holes for receiving foundation girders, laying girders horizontally in the trenches, flexibly connecting the girders to one another, squaring and leveling the flexibly connected girders, pouring concrete footings into the column holes to support the squared and leveled girders permanently, and erecting the structure of a building upon the girders as a foundation.
